TILE FLOOR

Filed July 19, 1928

Julien A. Bried

UNITED STATES PATENT OFFICE

JULIEN A. BRIED, OF OAKLAND, CALIFORNIA

TILE FLOOR

Application filed July 19, 1928. Serial No. 293,834.

This invention relates principally to tile floors composed of rigid tiles flexibly laid, of the character disclosed in my prior Patent Number 1,306,246, and has for its objects improvements thereon, also any floor or pavement laid with blocks or slabs in the manner to be described and claimed.

In the above mentioned patent I show a tile floor in which each tile is of flat triangular form supported at its underside at its corners only on short legs, so that each tile formed a tripod to stand firmly on any kind of a sub-floor or foundation independent of neighboring tiles. The tiles had their edges slightly beveled making the tiles slightly wider at the bottom so that when laid in abutting relation the seams were narrower at the bottom, or were what are commonly known as caulking seams. In the patent the bottoms of the seams are shown caulked with a piece of string or the like, and above the caulking material was run a small quantity of melted pitch or tar.

In trying out floors laid as above, many difficulties presented themselves. The beveled or caulking seam edge tiles were expensive to manufacture, the tiles could not always be held in abutting relation and the caulking material would be forced into the space underneath the tile to thereby lift it and destroy its three point support. Also the pitch or asphaltum was extremely difficult to run to just the right height in the seams and was very difficult to clean off if overrun. Besides, no pitch or other similar meltable compound entirely suitable to stand the hottest weather or hot places in rooms near radiators could be found, and there was always the danger of the seams becoming sticky, especially if the floors were waxed, or cleaned with a little kerosene or other solvent.

I have discovered how to overcome all of the above and other difficulties and make the three-cornered self aligning tile floor practicable, easy to make, easy to lay, make its seams permanent, and for a given thickness of tile increase its load carrying capacity very greatly and also make it much less liable to break from sudden shocks.

In the drawing accompanying this application Fig. 1 is a plan view of a portion of my improved tile floor as laid with three-cornered tiles. Fig. 2 is a substantially full size sectional view of Fig. 1 as seen from the line 2—2 thereof. Figs. 3 and 4 are plan and end views of a spacer used to separate the tiles, and Fig. 5 is a plan view of another form of spacer.

At the time of taking out my former patent I felt that a clear space would have to be maintained under each tile in order to preserve its self aligning features, hence the tightly abutting lower edges and caulking of the lower part of the seams to prevent any of the pitch or other flexible cement from running through and getting under the tiles.

However I have now discovered that if the caulking seams are dispensed with and a flexible cement such as pitch, tar, asphaltum, or compounds thereof is run molten or in a fluid condition into the bottom of the seams, and preferably underneath the entire lower surface of the tile so as to fill the gap between the supporting or base floor and the bottom of the tile, a totally different result is obtained, as this flexible cement preferably runs hot, cements the tiles to the base floor, but since the cement when set is not rigid it permits each tile to still rest solidly on its legs or supports at all times with any changes or settling, or vibration of the supporting floor, yet the material being quite firm under the body of the tile will contribute many times to the load carrying capacity of the tile above, as well as enable it to stand a much greater shock without fracture.

The material which I have found best for the purpose is asphaltum pitch or coal tar pitch of relatively high melting point and preferably filled with earthy or fibrous matter such as ground asbestos, volcanic ash, diatomaceous earth, etc. which greatly reduce the tendency of the pitches to fracture upon shock when cold, or to creep in hot weather, and also increase their load carrying ability, though other flexible cements may be used.

With diatomaceous earth as a filler I have used up to several times the volume of the pitch with satisfactory results, the limit in

quantity of filling material being the point where it becomes too difficult to apply under the tiles or in the seams, though it is easier to apply a somewhat stiffer mixture under the tiles.

5 The flexible cement is not filled to the top of the seams, but preferably only about half way up, and above this the seams are filled with a substantially rigid cement such as 10 magnesite flooring cement. The magnesite flooring cement composition will adhere to the tiles and also to the pitch cement below, and it forms a thermal insulator for the pitch so that it is not exposed to any direct rays of 15 the sun, and it also serves to confine the pitch cement so that it cannot flow or creep even if warm, or if the floor is not level.

Just what the relation between the two cements is, it is hard to say, but the pitch, especially coal tar pitch, will penetrate quite 20 deeply into the magnesite layer if hot, indeed considerable liquid tar may be mixed directly with magnesite cement after the magnesite oxide material has been mixed 25 with the aqueous solution of magnesium chloride, and will not stop it from setting. Hence the cements are not antagonistic.

I have also used Portland cement as a seam 30 filler above the pitch seam or lower layer of pitch, but I prefer the magnesite flooring cement as it is not entirely rigid; depending on the amount of fiber ground into it; and its slight flexibility in each joint permits considerable vibration to a floor as a whole 35 without cracking of the seams. In fact test floors placed where they would be stamped upon for months have not shown any cracking of the magnesite seams above the pitch, though should any cracks form in the seams 40 the pitch below would bleed into and heal them in a short time.

For outdoor work I preferably melt a layer of paraffine or floor wax into the magnesite seams after they are well set.

45 In the drawing the tripodal flat tiles are designated 1, their legs 2, standing upon a wooden or any suitable foundation or base floor 3, pitch seams 4, pitch underneath support 5, magnesite upper or insulating seams 6.

50 In Fig. 1 border tiles 1' of oblong shape are also shown, and these have a leg under each end only as shown at 2', it being understood that a tile resting on three points or less is self aligning, tho as worked out the present invention has value in some phases with tiles which have any number of supporting points underneath.

55 The tiles preferably have vertical edges as shown and are spaced from one another by 60 means of some type of spacer which will not stop the flow of the melted pitch being applied. A good spacer is a short helical coil of wire 9 as shown in side elevation and end elevation respectively in Figs. 3 and 4.

65 Another form of spacer is the star shaped

wire device 10 shown in plan in Fig. 5. In this device the wire loops have their extreme ends 10' bent upwardly at right angles to the plane of the radial arms. The arms or loops of wire were originally extended in one plane 75 as indicated by the dotted extensions 10" before the ends were bent upward. This wire star has six arms to space the junctures of six triangular tiles shown in Fig. 1, tho it is evident that it may have fewer arms to space 75 fewer tiles if desired.

Either type of spacer described is dropped into position when the tiles are laid and permits the molten pitch to run through. In laying a floor I preferably first lay the tiles 80 loosely in place with spacers between, then I consecutively lift each one (with a rubber vacuum cup) and pour a pool of the melted pitch on the supporting floor and at once lower the tile upon it pressing down firmly to 85 squash out any surplus pitch and bring the tile legs down hard on the base floor. When all are thus firmly cemented to the base I then run more of the melted pitch, or a lighter grade thereof into the seams to about half 90 fill the same, and after cooling fill up the seams with the magnesite cement as described, preferably smoothing and compacting the seams after the cement is partially set.

95 For exposed porch floors I preferably coat the whole wooden supporting floor first with a coat of tar or asphalt, or pour a sufficiently large pool under each tile in laying them so that a film will run under the legs of the tiles also at 7. Tho if the pitch is very hot and fluid it will permeate under the legs with the ordinary procedure described.

If no pitch is deliberately poured under each tile as laid, it will nevertheless run under the tiles quite a distance in pouring the seam, but lack of entire filling of the spaces under the tiles will not cause the level of the pitch to fall in the seams if the pitch is of the proper body and/or filled as described.

100 In its most complete form the invention will be seen to comprise a tile floor wherein each tile is supported in a self-aligning manner on three short legs resting on a base floor to carry the load, and that the tiles are additionally supported to carry the traffic by a firm tho slightly yielding material beneath the body of the tiles between the supporting legs, and which additional support can always yield slightly so as to preserve the self-aligning features of the tiles on their three legs and keep them solidly on the base at all times. Also that said additional support cements the tile to the base, and stabilizes the tiles against shocks from above, therefore functioning in a manner entirely different from the earlier disclosure wherein the tiles were loose from the base floor and there was nothing but an empty space below each tile 105 110 115 120 125 130.

and the edges were abutted and caulked in a manner to keep the spaces empty.

Also, it should be noted that the flexible cement used under the tiles fills the lower part of the seams, and that contrary to the earlier disclosure the upper part of the seams are left unfilled with the flexible cement, but are filled with another cement having different properties from the flexible cement below it, principally heat insulating properties so as to protect the flexible cement, and seal it away from the air entirely under the tiles or at the bottom of the joints so that it will not melt and ooze out, stick to peoples' shoes, or rugs, or dissolve when oil or volatile solvents are used to clean the floor, or slowly flow along the seam in the manner of the pitch cements in sidewalk joints.

Another point to be noted is the fact that the spaces below the tiles and the seam spaces are in free communication so that the flexible cement when poured can readily flow through, yet the tiles are rigidly spaced by spacers which permit this flow yet also function to prevent any gradual creep or displacement of the tiles through constant traffic in one direction, or if they are laid on a slanted floor like an outside porch floor, and further that the tiles are additionally rigidly spaced by the rigid or substantially rigid top filler in the seams.

The use of the word pitch or flexible cement in my claims is intended to embrace any type of caulking pitches, tars, asphalts, or compounds which may be put in place in a liquid, semi-liquid or plastic condition and which when set are slightly flexible, and whether any of the same are filled with other material or not.

The word tile as used herein means rigid or substantially rigid flat tiles, blocks, or slabs, as used on floors or pavements and whether made of pottery ware, cement, glass, or any other hard material adapted to stand on short legs or supports, and in some phases of the invention when supported on a base with or without legs or other supports, all as fall within the scope of my appended claims. Also, the word "floor" as used in the claims means any surface or walk which may be walked upon.

I claim:

1. A tile floor comprising rigid tile units supported on a base, flexible cementing material securing the tiles to said base, and a filling of relatively non-flexible cement in the seams of the tiles.

2. A tile floor comprising rigid tile units supported on a base, flexible cementing material securing the tiles to said base and extending part way up the seams between the tiles, and the upper portion of the seams filled with a relatively non-flexible cement.

3. A tile floor comprising rigid tile units supported on a base, flexible pitch cement ma-

terial securing the tiles to said base, and a filling of relatively non-flexible cement in the seams between the tiles above the pitch.

4. A tile floor comprising rigid tile units each supported on three legs on a base, flexible cementing material securing the tiles to said base, and a relatively non-flexible cement filling the seams between the tiles. 70

5. A tile floor comprising rigid tile units supported on a base, spacing elements between said tiles, flexible cementing material securing the tiles to said base, and a filling of relatively non-flexible cement in the seams between the tiles. 75

6. In a tile floor as specified in claim 5, said spacing elements arranged to permit the flow of a fluid cement therethrough. 80

7. A tile floor comprising floor tiles each supported on short legs on a base floor, pitch in the spaces between the legs under the tiles and in the lower part only of the seams between the tiles. 85

8. A tile floor comprising flat tiles each supported on short legs on a base floor, pitch in the spaces between the legs under the tiles and in the lower part of the seams between the tiles, and a relatively rigid cement in the seams above the pitch. 90

9. A tile floor comprising flat tiles each supported on short legs on a base floor, pitch in the spaces between the legs under the tiles and in the lower part of the seams between the tiles, and a magnesite cement filling the upper part of the seams above the pitch. 95

10. A tile floor comprising rigid tile units supported on a base floor, a flexible cement securing the tiles to the base, and a magnesite cement filling the seams of the tiles. 100

11. The method of laying a tile floor which comprises placing a quantity of liquid flexible cementing material under each tile, pressing the tile in place, and of filling the seams between the tiles part way only with flexible cementing material. 105

12. The method of laying a tile floor which comprises placing a quantity of molten flexible cementing material under each tile, pressing the tile in place, and filling the seams between the tiles part way only with molten flexible cementing material. 110

13. The method specified in claim 12 plus after solidifying of the molten material, filling the remainder of the seams with relatively non-meltable cementing material. 115

14. A seam joint in a tile floor comprising flexible cement at the lower part of the seam, and the upper part of the seam filled with a substantially rigid cement. 120

15. A seam joint in a tile floor comprising pitch at the lower part of the seam, and the upper part of the seam filled with a magnesite cement. 125
